ABRAHAM PODEL, OF LONG ISLAND CITY, NEW YORK, ASSIGNOR TO ANCHOR CAP AND CLOSURE CORPORATION OF LONG ISLAND CITY, NEW YORK, A CORPORATION OF NEW YORK

CAPPING MACHINE

Application filed October 16, 1924. Serial No. 743,870.

The present invention relates to capping machines and more particularly to machines adapted to apply caps to a group of containers.

An object of the present invention is to provide a machine more simple in operation and less expensive in construction than automatic capping machines, and at the same time, to provide a machine which will apply caps to containers at a very high rate.

Another object is to provide a machine to which containers may be supplied manually in groups and which is adapted to apply caps simultaneously to a number of containers to increase the rate of capping and facilitate the feeding of containers.

Another object of the invention is to provide a cap pressing member having a plurality of pressing heads yieldably held in position to engage individual containers and to apply caps thereto; to provide trays adapted to slide in guide ways on a table under the pressing member and maintain a group of containers correctly positioned for the operation of the pressing member; and if desired, to maintain another group of containers in readiness to be placed in capping position.

A further object is the provision of supporting means for said pressing member comprising a pair of toggle-joints pivotally connected to a shaft so that the rotation of the shaft operates the toggle-joints to raise and lower the pressing member; and the adjustment of their relative positions so that maximum pressure is applied to the caps when the toggle-joint is near its straight position; thereby minimizing the power required to operate the machine.

Another and further object of the invention is the provision of a pressure applying mechanism suspended by a pair of toggle-joints attached to the respective ends of said mechanism, with the toggle joints being eccentrically connected to a rotating shaft to raise and lower said pressure applying mechanism,

and with said eccentric connections and said toggle-joints being adjusted so that the maximum pressure will be applied to said mechanism when said connections and said toggle-joints are substantially in straight positions. 50

Further objects contemplate a rigid construction comprising a table and a framework for supporting the various mechanisms formed of a minimum number of parts which may be readily obtained from available 55 sources; to provide adjustments to render the machine applicable to various types of containers and to regulate the pressure applied to the caps; and to provide means for supplying the cap applying mechanism without 60 cutting off the power supplied to the machine.

Other and further objects of the present invention will in part be obvious and will in part be pointed out hereinafter in the specification following by reference to the accompanying drawings in which like characters 65 refer to like parts throughout.

Fig. 1 is a front elevational view of the capping machine with certain portions shown in section. 70

Fig. 2 is an end view of the machine with certain parts broken away to clarify the drawing.

Fig. 3 is a cross-section along the line 3—3 in Fig. 1, showing the toggle mechanism in 75 bent position.

Fig. 4 is a cross-sectional view along the line 4—4 of Fig. 1, showing details of the mechanism.

Fig. 5 is a cross-sectional view with certain 80 portions in elevation showing the interior of the pressing member and the trays adapted to position the containers.

Various ways have been utilized heretofore for the application of caps to containers. 85 Generally speaking, the caps have been applied either by hand, or by automatic machines requiring conveyors and various other associated mechanisms. Hand methods are slow and expensive, since labor is high and 90

since an individual can apply only a limited number of caps a day. Furthermore, as he grows tired of such uninteresting work, he becomes careless and fails effectively to apply the caps to the containers. Automatic machines eliminate some of these difficulties and usually comprise a continuous conveyor which moves containers to a capping station at which they are stopped and the caps applied, and from which they are moved by a second conveyor. The stopping and starting of the filled containers frequently slops their contents over the sides of the vessels and necessitates the vessels being washed before the labels are applied. In addition to this disadvantage, these machines are extremely expensive and require a great amount of space for their proper operation. Small manufacturers frequently do not have the space necessary and cannot afford to make the investment required to properly install such machines.

The present invention eliminates the difficulties of the prior art by providing trays adapted to hold a dozen or more containers, supplying these trays to a capping machine which applies caps to a group of containers simultaneously. A second tray may push the first one out of the way while the former is being placed under the pressing head. The result is that the pressing machine which is simple in construction and inexpensive in manufacture can cap groups of vessels consecutively as quickly as an operator can place trays holding containers under the pressing member. Inasmuch as the containers remain on the trays during the filling, capping and sealing operation, the output of the machine is limited only by the ability of the operator to handle the trays, and the speed of capping may approach or exceed that of an automotive capping machine.

The cost of the machine is further reduced by the provision of toggle-joints for supporting the pressing member and the further provision of eccentric connections at right angles to those supporting the pressing member to operate the same, thereby utilizing the double effect of the toggle-joints and eccentric connections to minimize the power required to exert a maximum pressure on the containers during the capping operation. This decreases both the size of the parts and the cost of the machine. Suitable means are provided for rendering the motive force effective or ineffective upon the pressing mechanisms to keep the machine under complete control of the operator.

Referring to the drawings, there is provided a table 1 having legs 2 securely held in position by bolts 4 extending transversely thereof. The table legs 2 are flanged at their lower ends as shown at 5 to form a flat surface for engagement with the floor and are flanged

at their upper ends as shown at 6 to receive a slab 7 which forms the top of the table.

Mounted on the slab 7 is a pair of channel members 8 and 9 flanged at their upper and lower ends to fit upon the table and to accommodate a bracing member 10 which fits across their upper ends. Suitable bolts 11 preferably four in number, pass through the bracing member 10, the flanges at the upper and lower ends of the upright members 8 and 9, and the slab 7 of the table 1 to hold the framework rigidly on the table. The upright members 8 and 9 have channels facing outwardly and have on their inner flat portions a pair of guideways 12 and 14 adapted to receive runners 15 and 16.

A pressing member 17, which will be described in detail hereinafter, is attached to the runners 15 and 16 and adapted to slide vertically in the guideways 12 and 14. A pair of toggle-joints 18 and 19, pivotally secured to the bracing member 10, are secured at their lower ends to pins 20 fitting across slots 21 in the ends of the pressing member 17, as shown in Figure 3. Each toggle-joint comprises an upper link 22 attached to a lower link 23 by a pin 24. The link 23 is broken in its center with the ends threaded at 25 and 26 to fit into the sleeve 27, having apertures 28 arranged to receive a spanner wrench for adjusting the length of the toggle-joint to determine the extreme positions of the pressing member 17. A lock nut 29 is threaded on the member 25 to lock the sleeve 27 in position and prevent the vibrations of the machine from changing the desired adjustment.

Attached also to the pin 24 is an arm 30 pivotally and eccentrically mounted on the shaft 31, by a bolt 32 and sleeve 34. The arms 30 eccentrically mounted on the shaft 31 form in effect a second pair of toggle-joints acting at right angles to, and adapted to operate the toggle-joints 18 and 19. This construction permits a compound toggle effect to raise and lower the pressing member 17 upon rotation of the shaft 31.

An electric motor 35 is operatively connected to the shaft 31 through gear 36, on motor shaft 37, gears 38 and 39, on shaft 40, and gear 41 on shaft 31. The gear 41 is loosely mounted on shaft 31 and is adapted to be rigidly connected thereto by a clutch 42, of any suitable type. Preferably, the clutch comprises a sleeve 44 keyed to shaft 31 at 45 and having a slot 46 with a pin 47 therein. A spring 48 presses the pin 47 toward the gear 41 to cause it to engage the slot 49 and to connect the gear 41 to sleeve 44. A collar 50 bolted to the sleeve 44 retains the pin 47 in position. For the purpose of disengaging the clutch, a member 51, having a cam surface at its end adapted to engage a slot 52 in pin 47, is adapted to fit in the annular runway 54, whereby the member 51, when in its lower position, engages the pin 47 as the shaft

31 is rotated and presses the pin to its outward position as shown in Fig. 1. The member 51 fits in a suitable bearing 55 in bracing member 10 and is connected by the links 56, 57, 58 and 59 to the handle 60. Accordingly, when the handle is moved downwardly about its pivot 61, the link 57 through its pivot 62, pulls the member 51 out of engagement with the pin 47 and when the gear 41 has rotated sufficiently, it engages in the slot 49 thereof to connect it rigidly with shaft 31 to operate the machine.

The pressing member 17 comprises a block 64 with extensions 65 at its ends. A series of cylindrical apertures 66, preferably 12 in number, are formed in the block to accommodate cylindrical cups 67 having slots 68 near their lower ends. A cover 69 is secured to the block 64 by bolts 70 and fits over and closes the upper ends of the cylindrical apertures. Suitable bolts 71 extend through the cover 69 and are threaded into the cups 67 to retain them in position. Stems 74 of the pressing heads 75 extend into the cups 67 and are retained in position against the springs 72 by pins 76 fitting in slots 68 and limiting the outward movement of the stems. The pressing heads 75 are of suitable size to fit over the caps 77 of containers 78; their engaging surfaces are formed preferably by a layer of rubber or other suitable soft material 79 faced with fabric 80 secured to the pressing heads by cement or in any other suitable manner.

For the proper handling of containers, a tray 80 is provided and adapted preferably to seat twenty-four containers and having recesses 81 in its bottom to maintain the containers in position. A pair of guideways 82 fit into cooperating grooves 84 in the table to determine the lateral position of the trays.

In the operation of the machine, electric power is applied to the motor 34 which in turn drives the gear 41, loosely mounted on shaft 31, through gear 36 on the motor shaft and gears 38 and 39 on shaft 40. The clutch 42 controlled by handle 60 is adapted to connect gear 41 rigidly to shaft 31 which reciprocates the arm 30, eccentrically mounted on shaft 31 and also pivotally connected to pin 24, and through this member operates toggle-joints 18 and 19 to raise and lower the pressing member 17.

The operator of the machine is furnished with trays 80 having filled containers thereon with caps loosely applied. The trays are placed upon the table so that the runways 82 fit in the grooves 84 and the operator moves the tray until the first twelve containers are under the pressing heads 75. The member 17, in its vertical movement, causes the heads 75 to engage the caps and apply them to the vessels. The operator has ample time while the pressing member is being raised to adjust the other twelve containers under the press-

ing hands; or if he desires he may stop the pressing mechanism by moving handle 60 to operate clutch 42. A second tray filled with containers is then placed in front of the first tray and in being placed under the pressing member 17 pushes forward the first tray so that it can be removed by another operator, or if the machine is being operated by a single person, the motor may be timed so that the rays may be removed and replaced by the operator during the upward movement of the pressing member 17. The pressure applied to the respective caps 77 is controlled by the length of the toggle arms 18 and 19 and can be adjusted by rotation of the sleeves 27.

It will be noted, therefore, that there is provided in this invention a structure of simple and inexpensive construction, requiring but little space and adapted to be operated by a single person to apply caps quickly to containers. The necessity of automatic machines for small manufacturers is eliminated and the cost of capping is greatly reduced. As various changes may be made in the embodiment above set forth, without departing from the spirit of the invention, it is understood that all matter herein is to be interpreted as illustrative and not in the limiting sense. The scope of the invention is defined in the following claims.

Having thus described my invention, what I claim is:—

1. In a machine of the class described, the combination of a suitable framework, a pressing member adapted to apply covers to a group of containers simultaneously, a pair of toggle-joints attached to the framework and adapted to support said pressing member, a shaft mounted on the framework having a crank at the respective ends thereof, and a pair of rods connecting said crank to said toggle-joints to move said pressing member in an upward and downward direction to apply the caps to the containers, threaded adjusting sleeves on each of said toggle-joints for changing the length thereof to control the extent of vertical travel.

2. In a machine of the class described, the combination of a table, a pair of upright members flanged at their respective ends, and mounted on said table, a bracing member fitting on the upper ends of said members, bolts passing through said table, said bracing member and the flanges on said channel members to form a framework on said table, guideways in said upright members, a pressing member mounted in said guideways adapted to apply covers to a group of containers simultaneously, a pair of toggle-joints pivotally secured to said bracing member and said pressing member to support said pressing member, and a source of power mounted on said bracing member and operatively connected

to said toggle-joints to operate said pressing member by bending said toggle-joints.

3. In a machine of the class described, the combination of a table, a pair of upright channel members flanged at their respective ends and mounted on said table, a bracing member fitting on the upper ends of said channel members, bolts passing through said table, said bracing member, and the flanges 5 on said upright members to form a framework on said table, a pressing member adapted to press a plurality of caps on a group of containers simultaneously, a shaft connected to said pressing member to operate 10 same, and a source of power mounted on said bracing member for driving said shaft continuously for operating said pressing member. 15

4. In a machine of the class described, the combination of a table, a pair of upright channel members flanged at their respective ends and mounted on said table, a bracing member fitting on the upper ends of said channel members, bolts passing through said 20 table, said bracing member, and the flanges on said channel members to form a framework on said table, a pressing member adapted to press caps on containers, a shaft mounted in said framework, devices pivotally 25 connected to said shaft, a pair of toggle-joints supporting said pressing member from said bracing member and connected to said devices, adjusting means on said toggle-joints to control the pressure applied to said 30 caps, and mechanism for driving said shaft continuously. 35

5. In a machine of the class described, a pressing member comprising a block having a plurality of apertures formed therein, a 40 cover on said block adapted to close one end of said apertures, and pressing heads having stems adapted to fit in said apertures.

6. In a machine of the class described, a pressing member comprising a block having a plurality of rows of apertures formed therein 45 in said rows extending longitudinally and transversely thereof, a cover on said block adapted to close one end of said apertures, pressing heads having stems adapted to fit in said apertures, resilient means in said apertures to press said stems outwardly, and means to limit the outward movement of said 50 pressing heads.

7. In a machine of the class described, a pressing member comprising a block having a plurality of apertures formed therein, cups rigidly secured in said apertures, pressing 55 heads adapted to apply caps to containers and having stems fitting in said cups, resilient means in said cups to press said stems outwardly, and means to limit the outward movement of said pressing heads.

8. In a machine of the class described, a pressing member comprising means having 60 a plurality of apertures formed therein, cups

fitting in said apertures having slots therein, a cover on said block rigidly secured thereto, pressing heads adapted to apply caps on containers and having stems fitting in said cups, resilient means in said cups to press said stems outwardly, and means fitting into said slots to limit the outward movement of said pressing heads. 70

9. In a machine of the class described, a pressing member comprising a block having a plurality of apertures formed therein, cups fitting in said apertures, and having slots in the sides thereof, a cover on said block rigidly secured thereto and to said cups, pressing heads adapted to apply caps on containers and having stems fitting in said cups, resilient means in said cups to press said stems outwardly, and pins extending through said stem and into the slots in said cups to limit the outward movement of said pressing heads. 75 80

10. In a machine of the class described, the combination of a suitable framework, a block having a plurality of apertures therein, pressing heads having stems adapted to fit in said apertures, resilient means in said apertures to press said stems outwardly, a pair of guideways in said framework adapted to engage the ends of said block, a pair of toggle-joints adapted to suspend said block from said framework, and a source of power operatively 90 connected to said toggles to raise and lower said block by bending and straightening said toggle-joints to apply caps to a group of containers simultaneously. 95

11. In a machine of the class described, the combination of a suitable framework, a block having a plurality of apertures therein, pressing heads having stems adapted to fit in said apertures, resilient means in said apertures to press said stems outwardly, a pair of guideways in said framework adapted to engage the ends of said block, a pair of toggle-joints adapted to suspend said block from said framework, a shaft on said framework having a pair of cranks thereon attached to said toggle-joints, and a source of power for driving said shaft to raise and lower said block for applying caps to groups of containers. 100 105

12. In a machine of the class described, the combination of a table adapted to receive a tray of containers, a pair of vertical members mounted on said table, a horizontal bracing member joining the upper ends of the vertical members, a block having a plurality of apertures therein, pressing heads having stems adapted to fit in said apertures, a pair of guideways in said vertical members adapted to accommodate the ends of said block, a pair of toggle-joints adapted to suspend said block from said bracing member, means for raising and lowering said block, by bending and straightening said toggle-joints to apply caps to said containers, and means for adjusting the length of said toggle-joints to accommodate vessels of different heights. 115 120 125 130

13. In a machine of the class described, the combination of a suitable framework, a pressing member to engage and press covers on a plurality of containers simultaneously, supporting means for said member comprising a pair of toggle members attached to said framework and to opposite sides of said pressing member, said toggle members comprising two parts with adjustment sleeves joining the ends of the parts to lengthen and shorten said toggle members to regulate the pressure applied to said containers, and devices for operating said pressing member by bending and straightening said toggle members.
